UNITED STATES PATENT OFFICE.

WILLIAM J. LEIGHTY, OF SPRINGFIELD, MISSOURI.

FIRE-BOX FOR BOILERS.

1,117,145.

Specification of Letters Patent. Patented Nov. 10, 1914.

Application filed May 11, 1914. Serial No. 837,839.

To all whom it may concern:

Be it known that I, WILLIAM J. LEIGHTY, a citizen of the United States, and a resident of Springfield, in the county of Greene and State of Missouri, have invented a certain new and useful Improvement in Fire-Boxes for Boilers, of which the following is a description, reference being had to the accompanying drawings, which form a part 10 of my specification.

My invention, as disclosed in the drawings, relates more particularly to fire-boxes for the locomotive type of boilers, it being understood, however, that the invention may 15 be readily applied to boilers of various types.

One object of my invention is to provide a fire-box which will be provided with water-tube side walls, thus resulting in a fire- 20 box of greater safety than may be had with fire-boxes as at present in use.

A further object of my invention is the provision of a fire-box provided with water-tube side walls and an intermediate water-tube wall so that a considerably greater 25 heating surface area within the fire-box will be provided, thereby producing greater evaporative efficiency for the boiler due to the fact that the heating surfaces of my 30 improved fire-box will be substantially seven and six-tenths greater than that of the fire-tube area of the boiler.

Another object of my invention is the provision of a fire-box that will be more 35 economical in fuel consumption as a result of the increased fire-box heating surface relative to the total heating surface of the boiler; the construction being such that the fire-box heating surface is so disposed that 40 it will absorb the greatest possible amount of heat units from the fire and hot gases of combustion.

Another object of my invention is the provision of a fire-box which will be simple 45 in design, as well as efficient and inexpensive; the fire-box being of a construction which may be made at a moderate cost without necessitating the employment of special or expensive machinery; and which 50 may be readily applied to any ordinary existing locomotive boiler through the mere replacement of the present type of fire-box; the fire-box to a considerable extent eliminating the difficulty heretofore encountered 55 in staying the fire-box and shell-sheets by

reason of the substitution of the water-tubes and chambers of headers at the top of the fire-box, as well as the substitution of a heavy, hollow mud-ring at the bottom; the arrangement of the water-tubes or heating surfaces of the fire-box being such, however, as not to interfere with or baffle the hot gases in their passage through the fire-flues of the boiler.

The advantages above set forth, as well as other advantages inherent in the construction, will be readily apparent from the following detailed description of the accompanying drawings, wherein:—

Figure 1 is a perspective view of my improved fire-box with a portion of the boiler, of the locomotive type, shown secured thereto, and with the outer lagging of the fire-box shown omitted and a portion of the side wall of the fire-box shown in section in order to disclose the internal construction. Fig. 2 is a longitudinal sectional view, in perspective, of the fire-box illustrated in Fig. 1; a portion of the intermediate section of the mud-ring being shown in side elevation, while the ends are shown in section. Fig. 3 is a transverse vertical section taken on the line A—A of Fig. 2, looking in the direction of the arrows. Fig. 4 is a perspective view of the throat-sheet of my improved fire-box. Fig. 5 illustrates the flue-sheet of my improved fire-box, in perspective, thereby more clearly illustrating the off-set sides for taking up lateral expansion. Fig. 6 is a perspective view of the door-sheet of my improved fire-box, illustrating the same provided with off-set sides for taking up lateral expansion. Fig. 7 is a diagrammatic view illustrating the method of laying out the top corners of the flue-sheet and door-sheet of my improved fire-box. Fig. 8 is a perspective view of the back-head employed in connection with my improved fire-box construction. Fig. 9 is a perspective view of my improved sectional mud-ring, with one side or section thereof being shown separated or detached from the remainder of the mud-ring, and with a portion of the assembled or remainder of the mud-ring shown in partial cross section in order to more clearly disclose the internal construction thereof. Fig. 10 is a perspective view of one of the intermediate portions of the crown-sheet, disclosing the openings for receiving the upper ends of the 100 105 110

water-tubes, some of which constitute the intermediate wall, while others partially constitute the side walls of the fire-box. Fig. 11 is a perspective view of one of the side portions of the crown-sheet, showing the openings which are adapted to receive the upper ends of the water-tubes which constitute the other or remaining portion of the side wall of the fire-box. Fig. 12 is a perspective view of one of the water-tubes which constitute a portion of the side walls of the fire-box, namely those whereby the outside longitudinal section of the mud-ring is connected with the outside section or portion of the crown-sheet. Fig. 13 is a perspective view of one of the water-tubes which constitute the other portion of the side walls of my improved fire-box, namely those whereby the longitudinal side sections 15 of the mud-ring are connected with the intermediate section or portion of the crown-sheet located on the same side of the fire-box as the section of the mud-ring from which the water-tube extends. Fig. 14 is a perspective view of a water-tube employed to constitute the intermediate row or wall of tubes, whereby the intermediate longitudinal section of the mud-ring is connected with the intermediate sections or portions 20 of the crown-sheet.

In the particular exemplification of my invention, as illustrated in Figs. 1 and 2, only a portion of the cylindrical barrel or shell of the boiler is shown, because the 25 boiler construction forms no part of my invention. The construction, as illustrated in the drawings, comprises a front water-leg formed by the throat-sheet 20 and the flue-sheet 21, as more clearly illustrated in Fig. 40 2; the throat-sheet and flue-sheet being secured or stayed together by means of the stays 22; the flue-sheet or rear wall of the water-leg being stayed to the barrel of the boiler by means of the braces or stays 23 and 24. The bottom of the front water-leg is formed by the transversely extending front end of the sectional mud-ring as shown at 25 in Fig. 2, where the front end of the mud-ring is secured between the bottom portions 45 of the throat-sheet 20 and the flue-sheet 21; the mud-ring being secured by means of the rivets 26, see Fig. 2, in accordance with the usual practice. The fire-box is provided with a back water-leg formed 50 by the door-sheet 27 and the back-head 28, which are stayed together by means of a sufficient number of stay-bolts 29, disposed throughout the opposing flat surfaces of said sheets; while the remainder or unstayed 55 flat portion of the back-head is stayed or secured to the roof-sheet 30 by means of the stay-braces 31, as very clearly disclosed in Fig. 2. The bottom of the rear or back water-leg is formed by the transversely extending rear end 32 of the mud-ring, which

is secured between the door-sheet 27 and the back-head 28 by means of the rivets 33, in a manner similar to that employed in connection with the front water-leg as heretofore described. The mud-ring is more 70 clearly set forth, in perspective, in Fig. 9, and preferably consists of two hollow longitudinal side-sections 34, 34, and an intermediate longitudinal hollow section 35. The longitudinal sections are provided at their 75 ends with the laterally disposed projections or arms in order to constitute solid transverse portions or ends which are formed by the projections or portions 34^a, 34^a, at both ends of the sections. In the particular exemplification of the invention, the projections are adapted to overlap the laterally projecting arms or portions 35^a, 35^a, at both ends of intermediate member 35; intermediate member or section 35 being provided 80 with the projecting arms or portions 35^a projecting from opposite sides of the member, as very clearly shown in Fig. 9. When assembled, the overlapping projections or arms of all the sections are properly secured 85 together as for example by means of rivets passing through the rivet holes 36. One object in constructing the mud-ring in the manner shown, is to obviate any difficulty 90 that might otherwise be encountered by reason of internal strain, were the mud-ring cast in one piece, as the sectional construction of mud-ring will relieve any internal strain that might be had if the mud-ring with its hollow sections were made in one 100 piece; and, furthermore, a mud-ring as illustrated can more readily be cast than if made as a single unit. The various longitudinal hollow sections 34, 34, and 35, of the mud-ring, are provided in their upper surfaces 105 with suitable openings or orifices 37 adapted to receive the lower ends of the water-tubes 38, 39, and 40, which are so arranged as to constitute the side walls and an intermediate wall of the fire-box. The under surfaces of 110 the longitudinal sections 34, 34, and 35, of the mud-ring are preferably also provided with openings 41, correlated to or in alignment with the openings 37 in the upper surfaces thereof. The purpose in thus arranging the openings is to permit the lower ends of the water-tubes 38, 39, and 40 to be properly rolled or swaged, or welded if preferred, into the orifices or openings 37 115 in the upper surfaces of the respective longitudinal sections of the mud-ring. The openings 41, provided in the bottoms of the respective longitudinal sections of the mud-ring, are normally intended to be closed by a suitable means, preferably by means of 120 threaded plugs 42, see Figs. 2 and 3; although any suitable means may be employed, as for example hand-hole covers and the like, whereby a fluid-tight connection may 125 be effected. The ends of the longitudinal 130

chambers of the respective sections 34, 34, and 35, are preferably made to terminate in the upwardly presented opening 43, whereby communication between the longitudinal chambers of the mud-ring and the front and back water-legs of the fire-box is established.

The upper part or crown of my improved fire-box is preferably composed of four longitudinally disposed channeled sections 44, 45, 46, and 47; the sections 44 and 47 being identical in general contour, as very clearly shown in Figs. 3 and 11, while the sections 45 and 46 are identical in general contour, 15 being preferably formed so as to provide a deeper channel than that of the side sections, as is very clearly disclosed in Figs. 3 and 10. The object in thus deepening the channel of the intermediate sections 45 and 20 46 is to enable the water-tubes leading thereto to be formed at the upper ends along as direct or straight lines as possible, without the necessity of providing the tubes with a reverse bend at the upper ends thereof, 25 which would tend to make the tubes difficult in cleaning. As very clearly shown in the figures just referred to, the sections are provided with the substantially perpendicular sides or flanges whereby the adjacent 30 sections are secured together by means of the intermediate calking strips and the sling-stay anchors 48, 49, and 50, as very clearly shown in Fig. 3. Secured to the roof-sheet 30 and preferably in vertical 35 alignment therewith and in an opposed manner, I provide the anchor-bars 51, 52, and 53, to which the crown-sections are secured or stayed by means of the sling-stays 54 connecting anchors 48 and 51, sling-stays 40 55 connecting anchors 49 and 52, and sling-stays 56 connecting anchors 50 and 53, thus providing a thoroughly stayed crown for the fire-box.

The inner side walls of the fire-box, as 45 previously stated, are formed by series of tubes disposed perpendicular to the bottom or mud-ring of the fire-box, with each alternate tube, namely the tubes designated as 38 extending from the side longitudinal sections 50 of the mud-ring to the outside longitudinally disposed channel-sections 44 and 47 of the crown-sheet. The other tubes, namely tubes 39, which, with tubes 38, form 55 the inner side walls of the fire-box, connect the side longitudinal sections of the mud-ring with the intermediate longitudinally disposed channel-sections 45 and 46 of the crown-sheet. The intermediate or substantially central wall of the fire-box is composed 60 of the tubes 40 which are connected to the intermediate hollow longitudinal section of the mud-ring, while the upper ends of the alternate tubes of the intermediate wall connect with the channel-sections 45 and 46, respectively, located on opposite

sides of the longitudinal center line of the fire-box.

The arrangement of the tubes as just described, is very clearly set forth in Fig. 3, from which it is apparent that circulation 70 may take place between the upper and lower parts of the fire-box, (aside from that existing between the front and back water-legs and the upper part of the fire-box), by means of the tubes which connect with the 75 various hollow longitudinal sections of the mud-ring.

As more clearly disclosed in Fig. 3, it will be noted that the longitudinally disposed channel-sections 44 and 47 of the 80 crown sheet of the fire-box, are secured at their outer edges to the roof-sheet 30 by the rivet seams 57 and 58, respectively, with an interposed liner 59, which also serves as a support to the upper portion 60 of the outside wrapper sheet of the fire-box, as very clearly shown in Figs. 1 and 3. The ends of the roof-sheet 30 are secured by means of the rivet seam 61 to the throat-sheet 20 at the forward end of the fire-box, and by 90 means of the rivet seam 62 to the back-head 28 at the rear end of the fire-box, as very clearly disclosed in Fig. 2.

The upper ends of the water-tubes 38, 39, and 40 may be secured to the respective portions of the crown-sheet in any well known manner, but I prefer to weld the same so as to form the ends of the tubes integral with the respective sections 44, 45, 46, and 47, of the crown-sheet. In practice, it is preferable to form or secure the upper ends of the water-tubes in the respective sections of the crown-sheet before the roof-sheet 30 is riveted into place, thus allowing ready access to the tubes as will be readily understood. 100 In case of repair or renewal of the tubes, the roof-sheet 30 can be quickly removed by cutting the rivets in the rivet seams 57, 58, 61, and 62, and by removing the pins in the 105 sling-stays 54, 55, and 56, and the pins in the stay-braces 31.

The back-head 28 is shown provided with a number of hand-holes 63, 63, whereby access to the rear end of the sections or portions in the upper part of the fire-box may be had, either for the purpose of inspection or for the purpose of inserting tools in the event of repairs within the fire-box above the crown-sheet; the hand-holes being provided with any suitable covers whereby a 110 water-tight joint may be effected.

As the various water-tubes 38, 39, and 40 are provided with a single bend or curvature, it will readily be understood that they 115 can, therefore, be easily cleaned by means of the well known type of flexible tube-cleaner, which may be inserted therein, from the crown-sheet ends of the tubes, made possible by reason of the hand-holes 63. The 120 importance of this construction will be 130

readily apparent, as the scale accumulating within the tubes can be readily removed, thereby insuring greater efficiency.

It is evident from the construction shown and described, that the pins at the ends of the stay-braces 31 may be removed, allowing the stay-braces to be dropped down onto the crown-sheet, or removed from within the fire-box, so as to permit the operator to enter the steam and water space above the crown-sheet in order that he can properly operate the cleaner; it being understood, of course, that the operator may enter the steam and water space through the steam-dome of the boiler as is usual in general practice; and one or more of the sling-stays 54, 55, and 56 may be removed to enable the operator to reach the water-tubes 38, located at the sides.

As disclosed in the drawings, the flue-sheet 21 at its upper end is preferably engrailed so as to provide the concave indentations corresponding with the transverse contour of the channel-sections 44, 45, 46, and 47, of the crown-sheet; and the sections of the crown-sheet are secured to the flue-sheet 21, the indentations whereof are preferably flanged rearwardly, as shown at 21^a in Fig. 5, so as to provide a substantially horizontally disposed portion which may overlap and be riveted to the forward ends of the channel-sections 44, 45, 46, and 47, as clearly disclosed in Fig. 2; the flange-portions 21^a of the flue-sheet 21 being formed so as to conform to the transverse contour of the channel-sections, as can be seen in Fig. 5. The rear ends of the respective sections of the crown-sheet are secured to the door-sheet 27 in a similar manner; namely the door-sheet has its upper end engrailed so as to provide concave indentations, similar to those in the flue-sheet, provided with the forwardly presented flanged portions 27^a, as very clearly shown in Fig. 6, which overlap the crown-sections and enable them to be riveted to the door-sheet in a similar manner to that previously described in connection with the flue-sheet. The manner of laying out the top corners of both the flue-sheet 50 and the door-sheet, in order to produce the engrailing and the flange portions described, is shown in the diagrammatic view in Fig. 7 where the dotted lines indicate the places where the sheet is to be bent so as to produce the construction of sheet previously shown and described. In order that a proper joint may be obtained, between the side, vertically disposed flange-portions 27^b of the door-sheet and 21^b of the flue-sheet, and the free ends 27^c, 27^c of the door-sheet and 21^c, 21^c, of the flue-sheet, I prefer to weld the disconnected or free ends 21^c and 27^c and thus form a water-tight connection.

In the preferable construction of the fire-box, I prefer to off-set the sides of both the

flue-sheet and the door-sheet and thereby reduce any internal strain that may be set up due to unequal expansion or contraction on account of the varied temperatures to which the different sections of the sheet are subjected. 70

Both the flue-sheet 21 and the door-sheet 27 are provided at their bottom ends with cut-away portions very clearly shown at 21^d and 27^d, in order to permit the flue-sheet and door-sheet to extend over and about the ends of the longitudinal sections of the mud-ring and enable them to abut against the transversely disposed portions of the mud-ring and yet permit communication 75 between the front and back water-legs and the longitudinally disposed chambers of the mud-ring; the flue-sheet and door-sheet, adjacent to the cut-out portions referred to, are riveted, or otherwise secured, to the vertically disposed portions 64 of the respective sections of the mud-ring, said portions being more clearly disclosed in Figs. 2 and 9.

From an examination of Figs. 2 and 3 the circulation of water and steam will be 90 clearly understood; the water will enter the chambers of the longitudinally disposed sections of the mud-ring from the front water-leg and from the rear water-leg, and in the normal or proper condition of the boiler, 95 the water will pass through the respective water-tubes 38, 39, and 40, thus permitting the water to circulate freely along the top of the crown-sheet, passing upwardly and downwardly through the water-tubes 38, 39, 100 and 40, in accordance with the temperatures of the various portions thereof.

As is clearly disclosed in the drawings, the water-tubes forming the side as well as the intermediate walls of the fire-box, are 105 preferably arranged to slope slightly forward from the bottom to top, for the purpose of accelerating the double circulation set within the tubes; it being understood that the tubes are of comparatively large 110 diameter. In arranging the tubes with a slightly forward slope as disclosed, the portions or globules of steam will have a tendency to collect along what may be termed the rear side wall of the tubes as the particles or globules of steam rise, thereby giving an opportunity for the colder water over the crown-sheet to flow downwardly along what may be termed the forward wall of the water-tube, and thus create an internal 115 circulation within the water-tubes. It is evident, therefore, that my improved construction provides a complete or generous circulation in all parts of the fire-box which are intended to contain water. 120

I prefer to form the intermediate sling stay anchor or bar 52 so as to provide reinforcing rings or portions 65 and 66 about the opening for the auxiliary dome and the opening for the steam-fountain, respectively, 125 130

thereby obviating the necessity of using separate liners for these boiler apertures, at the same time providing a suitable anchor for the sling-stays 55.

5 As more clearly disclosed in Fig. 4, I prefer to construct the throat-sheet 20 in a single piece, which is accomplished by pressing a sheet of steel into proper shape and thus simplify the operation of riveting up 10 the fire-box and making its proper connection with the boiler-shell.

It is understood, of course, that the throat-sheet, like the flue-sheet, is properly riveted to the transversely extending portions 15 at the forward end of the sectional mud-ring. These transversely extending portions are so formed, see Fig. 9, as to provide a suitable anchor or stay 67 between the throat-sheet and engine-frame; 20 while the transversely extending portions at the rear ends of the various sections of the mud-ring are formed so as to permit the back-head 28 to be riveted or otherwise secured thereto; and these transversely extending ends are shown provided with a 25 depending portion 68 which constitutes an anchor for the expansion pad between the back-head and the engine-frame.

By arranging the water-tubes in the manner shown and heretofore described, namely by having the successive tubes of the various series connected with different sections of the crown-sheet, it is apparent that they 30 form an open lattice work over the top of the fire-box, through which the hot gases may circulate and be permitted to impinge 35 against the bottom surfaces of the respective sections of the crown-sheet and thus permit of a more rapid heating of the boiler contents.

It will be understood, of course, that with the fire-box provided with the intermediate or central wall of water-tubes, the back-head of the fire-box and the door-sheet are 45 provided with two fire-door openings as shown at 69 in Figs. 1, 6, and 8, thus permitting proper access to both sides of the fire-box.

The spaces at the upper end of the fire-box, and at the sides thereof, may be provided with a fire-brick lining as shown at 50 in Fig. 3, secured against vertical displacement in any suitable manner and against lateral displacement by means of the water-tubes 38 and the sections 44 and 47 of the crown-sheet.

In addition to providing the door-sheet 27 with off-set sides 27^e, as very clearly shown in Fig. 6, I prefer also to provide 55 the door-sheet 27 with a bulge or pocket 27^e disposed longitudinally at a point intermediate of the fire-door openings 69; the pocket 27^e being preferably arranged to bulge into the water-leg intermediate of the 60 door-sheet 27 and the back-head 28, as very

clearly shown in Fig. 2. The object in providing the door-sheet 27 with the bulge 27^e disposed in a direction lengthwise of the sheet, is to compensate for the transverse expansion that may occur in the fire-box or 70 sides thereof and thus assist the off-set sides of the sheet in taking up or rather permit lateral expansion thereof.

I have shown and described what I believe to be the simplest and best form of 75 my invention and, therefore, do not attempt to show and describe all forms of construction that may embody my invention; but it is obvious from the foregoing description and illustrations that the invention may be 80 readily applied to different styles of boilers without, however, departing from the spirit of my invention; and I do not wish to be understood, therefore, as limiting myself to the exact construction shown and described. 85

What I claim is:

1. A fire-box of the class described, provided with a front and a back fluid-containing head, a crown-sheet composed of a series of longitudinally disposed channeled 90 sections, a sectional mud-ring provided with longitudinally disposed fluid-containing headers, and means disposed longitudinally of the fire-box, at the sides and longitudinal center thereof, whereby communication 95 between the longitudinally disposed headers of the mud-ring and the water space above the crown-sheet may be had.

2. In a fire-box, a mud-ring composed of a plurality of separable hollow longitudinal 100 portions provided with transversely disposed portions at the ends thereof whereby the longitudinal portions are secured together.

3. In a fire-box, a mud-ring composed of 105 two separable sides and an intermediate hollow longitudinal portion provided with openings in the upper surfaces thereof, and means whereby the sides and intermediate longitudinal portion are secured together 110 and maintained in proper relative position.

4. In a fire-box, a mud-ring composed of a plurality of separable hollow longitudinal portions provided with openings in the upper surfaces thereof, and means whereby 115 said longitudinal portions are secured together and maintained in proper relative position.

5. In a fire-box, a mud-ring composed of a plurality of separable hollow longitudinal 120 portions provided with openings so as to permit circulation therethrough, and means whereby said longitudinal portions are secured together and maintained in proper relative position.

6. In a fire-box of the class described, a mud-ring composed of a plurality of separable hollow longitudinal portions provided with openings at the ends thereof whereby 125 circulation from the water legs of the fire- 130

- box and through said sections may be had, and means whereby the longitudinal portions are secured together in proper relative position.
- 5 7. In a fire-box of the class described, a mud-ring composed of a plurality of separable hollow longitudinal portions the ends whereof are provided with solid transversely extending portions whereby the longitudinal portions are secured together in proper relative position.
- 10 8. In a fire-box of the class described, a mud-ring composed of separable hollow longitudinal portions, the ends whereof are arranged at an angle thereto so as to permit the portions to be secured together in proper relative position, and means whereby circulation through the hollow portions may be effected.
- 15 9. In a fire-box of the class described, a mud-ring composed of separable hollow longitudinal portions having openings in the top and bottom surfaces thereof, and means whereby the portions may be secured together in proper relative position.
- 20 10. In a fire-box of the class described, a mud-ring composed of separable hollow longitudinal portions adapted to form sides and intermediate sections, with the ends of the portions being formed at an angle thereto and arranged to overlap one another so as to permit the portions to be secured together and be maintained in proper relative position, and means whereby circulation through the sides and intermediate sections may be effected.
- 25 11. In a fire-box of the class described, a mud-ring composed of two separable side hollow sections and an intermediate hollow section, the ends of the respective sections being provided with solid transversely disposed portions whereby the respective sections are secured together and maintained in proper relative position, the sides and intermediate sections being provided with water-tube receiving openings in the upper surfaces thereof and correlated openings in the bottom surfaces thereof, and means whereby the openings in the bottom surfaces of said sections are normally closed.
- 30 12. In a fire-box of the class described, a mud-ring having hollow longitudinal sections open at the ends thereof, a flue-sheet the upper end whereof is engrailed and provided with horizontally disposed flange portions, while the lower end is provided with cut-out portions adapted to receive the ends of the longitudinal sections of the mud-ring.
- 35 13. In a fire-box of the class described, a flue-sheet provided with a flat flue-receiving portion and with vertically disposed flange portions arranged along the sides thereof, said flange portions being off-set, the upper end of the flue-sheet being indented or en- grailed, while the lower end is provided
- with cut-out portions adapted to receive the ends of the longitudinal sections of the mud-ring.
- 40 14. A fire-box of the class described, comprising a crown-sheet formed so as to provide a plurality of longitudinally disposed channels, means whereby the crown-sheet is suspended from the roof-sheet of the fire-box, a mud-ring provided with longitudinally disposed water-chambers, and a plurality of upwardly and forwardly presented water-tubes arranged intermediate of the longitudinal water-chambers of the mud-ring and the channels of the crown-sheet whereby circulation between the bottom and top of the fire-box may be had.
- 45 15. A fire-box of the class described, comprising a crown-sheet composed of separate channeled sections, means whereby the sections are secured together and suspended from the roof-sheet of the fire-box, a mud-ring composed of separate side and intermediate hollow sections longitudinally disposed of the fire-box, said sections being removably secured together and provided with openings in the upper surfaces and at the ends thereof, and water-tubes arranged in the openings of the mud-ring sections and extending upwardly to the crown-sheet sections whereby communication between the hollow sections of the mud-ring and the space above the crown-sheet is established.
- 50 16. A fire-box of the class described, comprising a crown-sheet composed of several channeled sections secured together and supported from the roof-sheet of the fire-box, a mud-ring composed of separate hollow longitudinal sections adapted to be secured together, and water-tubes of comparatively large diameter arranged intermediate of the hollow sections of the mud-ring and the channeled sections of the crown-sheet, said water-tubes being arranged to slope forwardly toward the upper ends thereof whereby circulation intermediate of the crown-sheet of the fire-box and the mud-ring and within the water-tubes will be induced.
- 55 17. In a fire-box of the class described, a plurality of water tubes of comparatively large inside diameter, said tubes being arranged in series so as to constitute an intermediate and two side walls within the fire-box, the tubes being provided with a single bend at a point intermediate of the ends thereof for the purpose of taking up unequal contraction and expansion.
- 60 18. In a fire-box of the class described, provided with a mud-ring having hollow longitudinally disposed portions with openings in the top surfaces thereof, and a plurality of water-tubes of comparatively large internal diameter, said tubes being arranged in series so as to constitute an intermediate and two side walls in the fire-box, the lower

ends of the tubes being reduced and secured in the openings of the mud-ring.

19. In a fire-box of the class described, anchor-bars longitudinally disposed of the fire-box and secured to the roof-sheet thereof, one of said anchor-bars being provided with ring-portions intermediate of its ends at points coincident with and extending about the auxiliary dome and steam-foun-
10 tain apertures of the fire-box.

20. In a fire-box of the class described, provided with a front water-leg formed by a single piece throat-sheet and a flue-sheet having off-set side portions, and a back water-leg formed by the back-head and the door-sheet, the latter being provided with off-set side portions, a crown-sheet composed of channeled portions extending longitudinally of the fire-box and removably secured
15 to the roof-sheet of the fire-box, a mud-ring composed of a plurality of hollow longitudi-
20

nal portions having openings in the ends thereof arranged in communication with the front and back water-legs of the fire-box, and a plurality of water-tubes arranged intermediate of the hollow portions of the mud-ring and the channeled portions of the crown-sheet so as to permit of circulation of water therethrough, said water-tubes being arranged to constitute the inner side walls
25 30 of the fire-box.

21. In a fire-box, a door-sheet provided with an off-set pocket or portion arranged to bulge into the rear water-leg of the fire-box, said pocket being arranged lengthwise of the sheet so as to allow transverse expansion
35 of the sheet.

WILLIAM J. LEIGHTY.
